(57) **CLAIM**

The ornamental design of the annular ice skate blade, as shown and described.

DESCRIPTION

FIG. 1 is a perspective view of the annular ice skate blade of my new design;

FIG. 2 is a front elevational view thereof;

FIG. 3 is a rear elevational view thereof;

FIG. 4 is a top plan view thereof, the opposite plan view and end elevational view are identical to FIG. 4;

FIG. 5 is a sectional view taken along line 5—5 of FIG. 2; and,

FIG. 6 is an enlarged sectional view of an outer portion of the blade of FIG. 5.
